DESIGN FOR A CARPET

John S. Travis, Long Island City, N. Y., assignor to Bigelow Sanford Carpet Co., Inc., a corporation of Massachusetts

Application April 11, 1935, Serial No. 56,325

Term of patent 7 years

To all whom it may concern:

Be it known that I, John S. Travis, a citizen of the United States, residing at Long Island City, in Queens County, and State of New York, have invented a new, original, and ornamental Design for a Carpet, of which the following is a specification, reference being had to the accompanying drawing, forming part thereof.

The figure of the drawing is a face view of a piece of carpet showing my design, the repeat unit of the design being contained within the area outlined by the dot and dash lines. This unit is repeated in the relation shown by the extensions beyond the unit boundaries.

I claim:—

The ornamental design for a carpet, substantially as shown and described.

JOHN S. TRAVIS.
